UNITED STATES PATENT OFFICE.

JOHN SCHADE, OF HOLYOKE, MASSACHUSETTS, ASSIGNOR TO NATIONAL BLANK BOOK COMPANY, OF HOLYOKE, MASSACHUSETTS, A VOLUNTARY TRUST ASSOCIATION OF COPARTNERSHIP, HAVING AS TRUSTEES F. B. TOWNE, E. S. TOWNE, J. M. TOWNE, AND F. W. WILSON.

BOOK COVER.

Application filed October 29, 1924. Serial No. 746,585.

To all whom it may concern:

Be it known that I, JOHN SCHADE, a citizen of the United States, residing at the city of Holyoke, in the county of Hampden and 5 State of Massachusetts, have invented certain new and useful Improvements in Book Covers; and I do declare the following to be a full, clear, and exact description of the invention, such as will enable others skilled 10 in the art to which it appertains to make and use the same.

This invention relates to book covers of the style shown and described in my U. S. Letters Patent No. 1,512,489, issued October 15 21, 1924.

But this improvement has nothing whatever to do with any particular style of hinging whereby the covers are connected with the back of the book, but relates solely to the 20 flexible side covers that are so formed that portions thereof will extend beyond either end of the hinged portion of the metallic back plate, the particular object being to prevent books of this sort from tearing the 25 pockets or scratching the desk.

Therefore in the following description no 30 special mention will be made of any particular form of complementary hinge elements that are carried by the metal back and by the side covers, since the present invention applies to all books of this particular style, as identified by my Letters Patent above referred to, irrespective of the manner in 35 which the hinge elements are formed and interconnected.

In the drawing

Figure 1 is a view of the inside of the book cover with the side covers fully opened—

Figure 2 is a similar view of the outside 40 of the book cover with the sides fully opened—

Figure 3 is a detail view of one form of the flexible covers the latter being fully opened, and

Figure 4 is a fragmentary plan view of a 45 slightly modified form of my invention with the parts detached.

Similar numerals of reference denote like parts in the several figures of the drawing.

1 is the metal back, having at its side edges complementary hinge elements 2, and 50 3 are the flexible side covers that are cut away so as to form a recess or jog 4 at their

inner portions, the length of this jog, which is the inner edge thereof, being equal to the 55 length of that portion of the metal back 1 which carries hinge elements.

This inner edge carries hinge elements 6 that are complementary to the elements 2 and are interconnected therewith so as to 60 form hinge connections between the covers and the back plate 1.

The formation of the jogs 4 leaves flaps 7 which are flexed toward each other and are secured together by any suitable clips 8, 65 as clearly shown in the drawings.

It will therefore be clear that I have provided flexible extensions of the cover that form a part of the back of the book so that there can be no danger of tearing pockets 70 in which the book might be placed or in marring a desk when the books are manipulated thereon.

In the invention as heretofore described, and as particularly identified by the construction shown at Figures 1 and 2, the side covers are made in two halves or sections, because it would be very expensive to form 75 these covers integral from a single piece of leather with the central portion cut away as 80 at 5, shown at Figure 3, owing to the fact that considerable leather would be necessarily wasted, and comparatively small pieces of leather could not be used at all, whereas if the covers are made in sections they can all 85 be cut out of smaller pieces of leather with no appreciable waste.

But the invention is the same whether the cover is made in sections or in one piece, and 90 therefore is not limited in this respect.

Referring particularly to Figure 4 it will be observed that the metal back plate 1 has extensions 9 at each end which make this plate substantially as long as the covers themselves, while the length of that portion 95 of the plate that carries the hinge elements 2 is substantially the same as the length of the jog in the covers as hereinbefore described.

There is no particular object in extending the back plate in this manner, except to show that such extension is fully within the scope of the invention.

What is claimed is:—

1. A book cover comprising a back and 100 side covers connected thereto by hinge ele-

ments, said covers having extension portions at their upper and lower ends which extend inwardly toward each other and substantially parallel with said back.

5. 2. A book cover comprising a metal back and side covers connected to said back by hinge elements, the side covers having portions above and below said metal back which extend substantially parallel with said back whereby flexible extensions are provided at the back of the book.

15 3. A book cover comprising a metal back having along its edges hinge elements, and flexible side covers that are longer than said back and are cut away at their inner portions to form recesses, the inner edges of said recesses being of substantially the same length as that of said back and having hinge elements secured thereto which are connected with the hinge elements of said back, said covers having portions that extend across the back of the book immediately beyond both ends thereof.

4. A book cover comprising a metal back having hinge elements at its side edges, and 25 separate flexible side covers that are longer than said back and have jogs cut in their inner portions the inner edges of said jogs being of the same length as that of said back and having secured thereto hinge elements that are commentary to the hinge elements of said back, said elements being interconnected whereby the covers are hinged to the back, the ends of the covers being flexed around at the back of the book immediately beyond the ends of the back and secured together in abutting relation. 35

5. A back cover comprising a metal back plate and cover portions hinged to said plate throughout the middle portion of their 40 length, the ends of the covers having extensions that form a part of the back of the book.

In testimony whereof I affix my signature hereto.

JOHN SCHADE.
